UNITED STATES PATENT OFFICE.

ALVIN L. FISHER, OF NEW BRUNSWICK, NEW JERSEY, ASSIGNOR TO THE
OVERMAN WHEEL COMPANY, OF BOSTON, MASSACHUSETTS.

OILER.

SPECIFICATION forming part of Letters Patent No. 350,124, dated October 5, 1886.

Application filed February 12, 1886. Serial No. 191,743. (No model.)

To all whom it may concern:

Be it known that I, ALVIN L. FISHER, of New Brunswick, in the county of Middlesex and State of New Jersey, have invented certain new and useful Improvements in Oilers; and I do hereby declare the following to be a full, clear, and exact description of the invention, such as will enable others skilled in the art to which it appertains to make and use the same.

My invention relates to an improvement in oilers, the object being to provide their spouts with swing-stoppers of reliable, durable, simple, and compact construction.

With these ends in view my invention consists in the combination, with a can and a spout therefor, of a tube extending transversely through the spout, and a swing - stopper pivotally attached to the spout through the said tube.

My invention further consists in certain details of construction and combinations of parts, as will be hereinafter described, and pointed out in the claims.

In the accompanying drawings, Figure 1 is a view, partly in elevation and partly in section, of an oiler embodying my invention; and Fig. 2 is a detached view in elevation of the swing-stopper.

The can A and removable stopper B of the oiler may be of any approved construction. The swing-stopper consists of a loop, C, formed of wire and having arms D D, a box, E, located between and secured to the ends of the said arms and open at one and closed at the other end, and provided at its closed end with an aperture, F, a plunger, G, located in the open end of such box and reciprocating therein, and a spiral spring, H, interposed between

the plunger and the closed end of the box, the said plunger being provided at one end with an opening, I, adapting it to fit over the end of the spout, and containing an elastic cushion, J, of cork or equivalent material for sealing the end of the spout, and at the other end with a stem, K, projecting through the aperture F of the box, and provided upon its projecting end with a button, L, through which the plunger is retracted into the box

against the force of the spring, which tends con-

stantly to force it in the opposite direction. A tube, M, extending transversely through the spout near the base thereof and constructed and arranged to permit the oil to flow around it and through the spout, affords a means for pivotally attaching the swing - stopper described to the spout, and this is done by passing the loop of the said stopper through the said tube, as shown. The spring of the stopper holds the plunger in place over the end of the spout, and causes the cushion in the plunger to seal the spout against the escape of oil. To use the oiler, the plunger is retracted into the box against the force of the spring by the button and the stopper swung aside. To seal the oiler again, the plunger is retracted by the button, as described, and the stopper swung into alignment with the tube, and the plunger being then released will be forced down over the end of the spout.

The spring of my improved stopper prevents the plunger from being accidentally displaced and the spout unsealed, while the tube and loop form effective means for permanently pivoting the stopper to the spout. If desired, the arms may be separated and hooked at their lower ends and introduced into the opposite ends of the tube, from which they might then be withdrawn and the stopper detached from the spout at pleasure.

Having fully described my invention, what I claim as new, and desire to secure by Letters Patent, is—

1. In an oiler, the combination, with a can and a spout therefor, of a tube extending transversely through the spout and a swing-stopper provided with arms entering the said tube, substantially as set forth.

2. In an oiler, the combination, with a can and a spout therefor, of a tube extending transversely through the spout and a swing-stopper provided with a loop extending through the said tube, substantially as set forth.

3. In an oiler, the combination, with a can and a spout therefor, of a swing-stopper having a plunger, a spring for controlling the same, a box for the plunger, and a spring and arms attached to the box and pivotally connected with the spout, substantially as set forth.

4. In an oiler, the combination, with a can and a spout therefor, of a swing stopper provided at one end with an opening containing a cushion and at its other end with a stem, a
5 spring for controlling such plunger, a box for the plunger and spring, and arms attached to the box and pivotally connected with the spout, substantially as set forth.

In testimony whereof I have signed this specification in the presence of two subscribing 10 witnesses.

ALVIN L. FISHER.
